UNITED STATES PATENT OFFICE

122,516

DESIGN FOR A COAT

Abraham Gruber, New York, N. Y.

Application July 24, 1940, Serial No. 93,885

Term of patent 3½ years

To all whom it may concern:

Be it known that I, Abraham Gruber, a citizen of the United States of America, residing in New York city, county of New York and State of New York, have invented a new, original, and ornamental Design for a Coat, of which the following is a specification, reference being had to the accompanying drawing, forming part thereof, wherein:

The characteristic feature of my design resides in the contrasting inserts in the two back pleats forming spearheads as shown.

I claim:

The ornamental design for a coat, as shown and described.

ABRAHAM GRUBER.
